[57] CLAIM

The ornamental design for a soft toy, as shown and described.

DESCRIPTION

FIG. 1 is a front view of a soft toy according to my novel design;

FIG. 2 is a right side view of a soft toy according to my novel design;

FIG. 3 is a left side view of a soft toy according to my novel design;

FIG. 4 is a bottom view of a soft toy according to my novel design;

FIG. 5 is a top view of a soft toy according to my novel design; and,

FIG. 6 is a perspective view from the rear of a soft toy according to my novel design.

The following features depicted in the informal drawings are not part of the claimed design: the fabric stitching lines apparent in some or all views of each embodiment of the soft toy, the lettering stitched onto the soft toy, zippers included in the soft toy, tags stitched into the soft toy, and the tube shaped portion affixed to the rear of the soft toy embodiment shown in FIGS. 1-6.
